UNITED STATES PATENT OFFICE.

TALLMADGE M. RICE, OF SPRINGFIELD, OHIO, ASSIGNOR TO WHITELEY,
FASSLER & KELLY, OF SAME PLACE.

AUTOMATIC GRAIN-BINDER.

SPECIFICATION forming part of Letters Patent No. 267,934, dated November 21, 1882.

Application filed April 21, 1880. (Model.)

To all whom it may concern:

Be it known that I, TALLMADGE M. RICE, of Springfield, Clarke county, State of Ohio, have invented new and useful Improvements 5 in Automatic Grain-Binders; and I do hereby declare that the following is a full and exact description of the same.

My invention relates to a machine for automatically separating a gavel from a flowing 10 stream of cut grain, compressing and binding the same, and discharging the bound bundles from the machine; and it consists in the combinations and arrangements of devices for transmitting motion from the prime motor to 15 the various devices whereby the bundle is separated, bound, and discharged.

That others may fully understand my invention, I will now particularly describe it, having reference to the accompanying drawings, wherein—

Figure 1 is a perspective view of my machine. Fig. 2 is a front end elevation, showing the gearing which forms the subject of this patent. Fig. 3 is a plan of my machine. Fig. 4 is a transverse vertical section. Fig. 5 is an elevation of the gearing-plate on the end of the machine. Figs. 6 to 13 are details of the devices for the initial driving movements. Figs. 14 to 30 are details of the devices for the 20 secondary driving movement.

A is the supporting-frame of the machine. Grain is delivered to the receptacle B by an endless apron or other suitable device. Motion is transmitted from the prime mover to 25 the main binder-shaft C by a chain, belt, or shaft, with gearing of any approved kind. From the main shaft C motion is communicated to the several operative devices by suitable gearing in train, and at the completion of the 30 binding of each bundle the motion of the machine is arrested and held at rest until the accumulation of delivered grain is sufficient to form another proper-sized bundle, when the 35 deterrent is automatically tripped and the binding machinery again set in motion.

At the end of the shaft C there is a bevel-pinion, D, which meshes with a similar bevel-pinion, E, upon the shaft of which there is also a small spur-wheel, F. For convenience

and compactness the spur-wheel F is in the 50 plane of the axis of shaft C, and is mounted upon a stud, a, which is rigidly secured to a mounting-plate, b, upon which also the bearings of shaft C are placed. The pinion F meshes with and drives the main wheel G, from 55 which all the groups of operative devices take their motion. One revolution of the wheel G completes the operation of separating, binding, and discharging one bundle.

The wheel G is provided with peripheral 60 flanges e and d, (see Fig. 18,) which flanges are not continuous, and is armed also with projecting trips or cams q t, the uses of which wheel and appurtenances are to impart intermittent rotations to the pinions in mesh with 65 said wheel, as hereinafter more particularly described.

The shaft C is provided with a clutch-sleeve, e, whereby it is coupled with the pinion D. (See Figs. 2, 8, 11.) A spring f on the rod m 70 (see Figs. 2 and 8) tends to throw said clutch into engagement, and it is retracted and carried out of engagement by a lever, g, which, at each revolution of the main wheel G, is caught by a stud, h, on said wheel and pulled down 75 until the clutch is retracted and liberated. To render this catch effective and sure, the outer end of the lever g is provided with a transverse orifice or socket, into which is fitted a bolt, i, Fig. 12, the end of which forms a cup, 80 as shown in Fig. 13, and this cup receives and holds the stud h. When the lever g has been moved far enough to disengage the clutch e the wheel G, and all the binding devices come to rest immediately. The bolt i may be withdrawn from its engagement with the stud h by 85 a bell-crank lever, j, and the spring f immediately impels the clutch into engagement, and the binder is started again, and so on.

The clutch-withdrawing device is made in 90 two parts, capable of motion through different distances, so that the motion of the withdrawing-lever g may be greater than the motion of the clutch-sleeve without causing any disaster to the parts. This is clearly shown in Figs. 2, 95 8, 11, where e represents the clutch-sleeve. k is the clutch-fork, and l the abutment against which the lever g presses. The fork k and the

abutment *l* both are mounted upon the rod *m*, the latter being fast and the fork loose thereon. The fork is held against the abutment by the spring *n*. When the fork has pushed the sleeve *e* back as far as it can go the springs *f* and *n* will still yield and permit the fork and abutment to separate.

All of the gearing which actuates the several devices and groups of devices have their 10 studs or bearings upon a single frame-plate, *H*, (see Figs. 2 and 5,) which is bolted to the front side or end frame of the binder, and serves to hold the parts of said frame in place, as well as to rigidly maintain in proper 15 relative position all of said bearings, and thereby keep in proper connection the several related and coacting parts.

I have now described those operative parts which are common to all the several groups of 20 devices which take their motion at one time and another from the main wheel *G*, confining the subject of this patent to the combination and arrangement of the driving-gearing and devices whereby the devices which separate, 25 bind, and discharge the bundle are severally actuated.

Starting with the initial movement of the main wheel *G* when the clutch *e* has gone into engagement, the first wheel in mesh with said 30 wheel *G*, which is moved thereby, is the pinion *J*. This pinion is made long enough to span the spur-teeth of the wheel *G*, and also the teeth of the pinion *K*. This is necessary because a part of the teeth of the pinion *J* in 35 range with the wheel *G* are cut away to form a segment and permit the pinion *J* to come to rest at each revolution, while with the pinion *K*, which is driven by the pinion *J*, the mesh must be continuous. At its back the pinion 40 *J* is provided with a crescent-plate, *p*, which at the proper time rests upon the flange *d* of the wheel *G* and prevents the pinion *J* from revolving. The pinion *J* is also provided with a double and long tooth, *o*, which meshes 45 with a corresponding recess in the pinion *K*. When in position of rest the pinions *J* and *K* are in mesh with the long tooth *o* in its recess, the plate *p* is on the flange *d*, with its front horn first coming in contact with the trip *q* on 50 the wheel *G*, whereby the pinion *J* is set in motion. (See Figs. 1, 18, 19.) The point or horn of the plate *p* passes down through one of the intervals in the flange *d* to permit said revolution. As the initial movement of the 55 pinion *J* is given by the point or horn of the crescent, it is slower than is due to the motion of wheel *G*, and the long tooth *o* equalizes this by imparting to the pinion *K* a relatively more rapid motion, and serves as a guide in 60 putting the gears together in proper time. The pinion *K* is mounted on the end of a shaft, *L*, the rear or inner end of which is supported in a bearing on the bridge-piece *M*, one end whereof is bolted to the inner cross-piece, *N*, 65 of the binder-frame, and the other end is supported upon the shaft *O*, the ends whereof are

in boxes on the end frames of the machine. The inner or rear end of the shaft *L* bears a crank, *q'*, whereby the separator or gaveler *P* is actuated. The separator *P* is mounted at 70 about its middle of length upon the crank *q'*. Its front or inner end is pointed and curved downward, so as to enter the stream of grain and pass through it easily. Its rear or outer end is provided with a laterally-projecting 75 stud, *r*, which slides in a long slot, *S'*, in the bridge *M*, and the front end or point of said separator therefore travels in an elliptical circuit, descending into the stream of grain, and, after thus separating it, moving the separated 80 part or gavel outward to the binder, and finally rising to its initial position. (Shown in Figs. 2 and 4.) During the time when the separator is in action all the remainder of the apparatus 85 is at rest; but when the separator has come to rest, then the wheel *Q* (see Figs. 2, 4, 17, 21) goes into action. The point of this wheel's crescent-plate *u* at that moment encounters the trip or starter *t* on the wheel *G*, and is directed 90 downward through the interval in the flange *c*, so that the wheel *G* is permitted to revolve. The wheel *Q* is provided with a radial arm, *v*, and a stud, *w*, at the end of the same, and said stud rests in a curved slot, *y*, in an arm, *R*. The arm *R* is mounted on the shaft *S*, which also 95 carries the cord-carrier and compressor *T*. The bearings of the shaft *S* are at opposite extremities of the frame *A*. However, it is only required that the shafts *S* and *O* shall extend entirely across the machine to avoid placing 100 boxes or bearings for them in positions where they would be exposed and might also obstruct the movement of the bound bundle in discharging. When the wheel *Q* revolves the stud *w* passes along the slot *y* and rotates the 105 shaft *S* until the point of the arm *T* has been carried up along the separator nearly to its highest limit, and at that moment the arm *R* commences to produce a movement of the shaft *O*, which carries the counter compressor-fingers 110 *a'*, Fig. 4, which are elastic to enable them to yield as required to conform to bundles of various sizes. The arm *R*, on the opposite side of the shaft *S* from the slot *y*, is provided with a slot, *b'*, transverse to the direction of the slot *y*, and in engagement with said slot there is the 115 rack *U*, which meshes with and drives the pinion *c'* on the shaft *O*. The rack-pin *d'*, engaging with the slot *b'*, is not operated until the movement of the arm *R* brings said pin to the 120 upper end, *e'*, of said slot, which takes place, as before stated, when the shaft *S* has completed the greater part of its rotation. The further rotation of the wheel *Q* carries the arm *T* to its 125 highest point and places the cord in position with reference to the knoter and cutter and end-holding gripper, and at the same time has carried the rack *U* downward, and has thereby rotated the shaft *O* to bring down the fingers *a'* and compress the bundle in circular form between said fingers and the arm *T*. When the 130 arm *R* is in position last mentioned, correspond-

ing with the completed compression of the bundle and placing of the band in the knotter, the curvature of the slot y corresponds with the path of the stud w , so that the continued rotation of the wheel Q leaves the band-carrier and compressors for a time at rest. During that period of rest the knotter unites the parts of the band and severs the cord, so as to leave it ready for a new bundle, and retains the end 10 leading to the spool or ball. When the knotter has completed its work the stud w will have traversed the curved part of the slot y and will re-engage the same at a point near its inner end, and the arm R will therefore be quickly 15 retracted, causing the rack U to retract quickly, and not only release the bundle, but cause its discharge by the discharger V on the shaft O . This latter effect is produced by the peculiar structure of the slot b' and rack U . At 20 the upper end of the slot b' there is a short lateral offset or angle e' , Figs. 2, 14, and at the extremity of the arm R there is a cross-head, f' . There is upon the rack U an inwardly-projecting arm and counterpoise or over-balancing weight, g' , and also an outwardly-projecting arm, h' . When the arm R has nearly 25 reached the upper extension of its motion, the arm g' encounters the arm R and pushes the pin d' into the offset e' , if it does not pass 30 thereinto without compulsion. The return motion of the arm R catches the pin d' in said offset e' , and the rack is pushed upward thereby until the arm h' shall strike the cross-head f' and push the pin d' out of said offset, and 35 thus permit the rack to fall to its initial position, with the pin d' at the lower end of the slot b' . The counterpoise g' also by its weight aids the descent of the rack, when liberated from the offset e' , and causes said rack to swing 40 so that the pin d' will enter and remain in the offset e' . It is this upward movement of the rack U which causes the quick retreat of the fingers a' and the equally rapid advance of the discharger V . 45 The rack U is confined in place in gear with the pinion c' by a pin i' , which stands out behind it from the plate H , and its downward movement is arrested when it encounters the head of the arm R . At the time of arrest the 50 fingers a' are in proper position to receive the new bundle.

As before stated, the action of the knotter and cutter is intermediate to the action of the cord-carrier and discharger last described.

The segment W , which operates the knotting, holding, and cutting mechanism, is provided with a flange, m' , which projects in the plane of its movement beyond the axis and opposite to the toothed segment. The flange m' 55 is constructed with two circular notches, $n' p'$, in its edge, and the axis of said segment is placed with reference to the wheels G Q so that said notches are alternately in the paths of the pins $k' l'$ on said wheels G and Q , respectively. Therefore, as the wheels G and Q revolve, the notch p' is first engaged by the

pin l' upon the wheel Q , and rotated until in its path said pin passes out of said notch. The notch n' is thereby brought into the path of the pin k' upon the wheel G , whereby the segment W is returned to its first position. 70

The knotting, cutting, and holding devices, and also the gaveler or separator and the binding-arm, are clearly set forth in another specification filed by me, of even date herewith, 75 and therefore are not claimed herein.

The bar which actuates the cutter and holder is coupled to a rod, F' , which extends through the plate H , and is actuated by one of the levers now to be described.

80

A stud, G' , projects in a radial direction from the segment W , and when at rest, before commencing its reciprocation, said stud is directly in line with and covers the axis of the knotter-barrel Y , and depresses the lever H' , which rests upon the rod d^2 , and pushes the central tying-hook outward and beyond the end of the short looping-cylinder. By the side of the lever H' the lever I' is placed, with its end resting upon the exposed end of the tubular rod a^2 . 90 Above the levers H' and I' the lever J' is placed, with one end upon the end of the rod F' , whereby the holder and cutter is actuated, and the other end in the path of the stud G' . Each of the levers I' and J' has its retracting-spring. The first 95 movement of the stud G' takes it off the lever H' , and releases the central tying-hook, which immediately retires within the looping-cylinder. The stud G' encounters the lever I' immediately as it releases the lever H' , and the outer gripping-hook is projected beyond the end of the barrel Y as the latter is beginning its rotation, and is immediately carried thereby in engagement with the binding-cord, which extends between the holder and the neck of the 100 looping-cylinder. The stud G' remains in engagement with the lever I' only long enough to allow the rotation of the barrel to carry the outer hook over the cord, and said hook is released and the cord is gripped. At the next 105 movement the lever J' is encountered by the stud G' , which passes under the free end of the same, and thereby causes the holder and cutter to be pushed forward, admitting the new cord to the notch, and upon 110 its retraction confining the cord and severing it between the holder and the knotter, so that the band-cord remains held by said holder only. When the stud G' passes off the shoulder s^2 of the lever H' and permits the inner 115

tying-hook to retreat, the retreat of the latter is arrested by the engagement of the free end of said lever H' with the spring-latch K' , and is so arrested until in its reciprocation the stud G' encounters said latch and again liberates 120 said lever H' and permits the said central tying-hook to fully retreat. On the return movement of the stud G' it engages the end i^3 of the lever I' , and, pushing the same outward, causes a quick advance of the outer gripping-hook and the release of the ends of the band-cord. When near the end of its move- 125

130

ment it again encounters the levers I' and H' and causes the inner and outer grippers or hooks to be again pushed fully out and liberate the band, the knot being finished. The backward movement of the segment W and stud G' causes the barrel Y to retrograde and the short looping-cylinder to advance again and all the parts to assume the positions they had at the beginning, ready for the next operation.

10. The arm T' is mounted loosely upon the shaft n²; but its range of motion is limited by shoulders on the head p², which is rigidly secured to said shaft. The arm T' is coupled with the bell-crank trip j by a rod, q², so that the latch 15 i is tripped and the binding mechanism is set in motion by the raising of the aprons S', and this occurs when sufficient grain has accumulated below them to form a bundle. The lost motion of the arm T' between the shoulders of 20 the head p² permits the aprons S' to rise a considerable distance before beginning to affect said arm or said trip.

Having described my invention, what I claim as new is—

25. 1. The clutch e, combined with the fork k, movable upon the rod m, and abutment l, fixed upon said rod, and provided with springs f and n, whereby the fork is moved backward by force applied to the abutment, but the latter may move farther than the former, for the purpose set forth.

2. The main spur-wheel G, provided with the discontinuous flanges c, d, and r'', trips q and t, and pin k', combined with three separate groups 35 of devices, all taking their movements from said wheel G in successive order—viz., the devices for separating the gavel, the devices for compressing, placing the band around, and discharging the bundle, and the devices for making and fastening the knot—as set forth.

3. The spur-wheel G, provided with the discontinuous flange d and stop q, combined with the pinion J, provided with the long tooth e and the crescent-plate p, and the pinion K, in 45 mesh with said pinion J, to drive the shaft L and gaveler with an intermittent motion, as set forth.

4. The wheel G, provided with flange d and stop q, the pinion J, provided with long tooth 50 o and crescent-plate p, and the pinion K and the cranked shaft L q', combined with the gaveler P, mounted at its middle upon the crank end q' of said shaft, and controlled at its rear end by the slot S^x, so as to have an elliptical 55 orbit at its front end, as set forth.

5. The bell-crank lever g, provided with the 55 detent-latch i and trip-lever j, combined with the wheel G, provided with the stud h, and the

clutch e, provided with abutment l, whereby the action of the wheel G withdraws the clutch 60 from engagement, and said engagement is established again by tripping said detent.

6. A main wheel provided with a discontinuous flange, d, and trip q, combined with a double pinion, J, one part whereof is a segment, 65 and which is provided with a crescent-plate, p, and long tooth o, and the pinion K in mesh therewith, whereby a continuous rotation of said main wheel will impart an intermittent but uniform motion to the pinion K and crank-shaft L.

7. The main wheel G, provided with a continuous row of spur-teeth and upon its sides with the laterally-projecting discontinuous flanges c d r'', trips q t, and pin k', combined 75 with pinion J, pinion Q, provided with pin l', and segment W, whereby said wheel successively actuates independent sets of mechanism, as set forth.

8. A main spur-wheel provided with a discontinuous flange, c, and trip t, combined with a segment-pinion, Q, provided with a crescent-plate, u, and an arm, v, and a slotted arm, R, in engagement with said arm v, and caused to move thereby with an intermittent vibration. 80

9. The vibrating arm R, provided with a curved slot, y, in one end, and in its opposite end a curved slot, b', transverse to the radial direction of said slot y, combined with the crank-wheel Q and the rack-bar U. 90

10. The vibrating arm R, provided with slot b' and offset e' therein, and the cross-head f', as described, combined with the reciprocating rack-bar U, provided with the projecting arm h' and weight g', whereby said rack-bar is successively pushed into and out of said offset e', as set forth.

11. The aprons S', mounted upon the rock-shaft N², whereby the inflowing grain is received and the bundle sized, combined with an arm, T', mounted loosely upon the end of said rock-shaft, and a shouldered head, p², rigidly mounted upon said shaft to permit a certain range of motion thereof without affecting said arm, and a rod, q², whereby the rocking of said rock-shaft through a certain arc will cause the detent i to be tripped and the binding mechanism set in motion. 100

12. The vibrating arm R, rack-bar U, pinion c' in mesh therewith, and shaft O, driven by said pinion, combined with the elastic compressor-fingers a' and discharger V, as set forth.

T. M. RICE.
